UNITED STATES PATENT OFFICE

EDMUND S. DELANCY, OF WASHINGTON, DISTRICT OF COLUMBIA

CALENDAR

Application filed December 10, 1931. Serial No. 580,192.

The present invention relates to new and useful improvements in calendars and has for its primary object to provide, in a manner as hereinafter set forth, a calendar embodying a novel construction, combination and arrangement through the medium of which any desired date or the day of the week upon which such date occurs or occurred within a given range of years may be expeditiously ascertained or, in other words, to provide a substantially perpetual calendar.

Other objects of the invention are to provide a substantially perpetual calendar which will be simple, efficient and reliable in use, attractive in appearance and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:—

Figure 1 is a view in front elevation of a calendar in accordance with the present invention.

Figure 2 is a vertical sectional view taken substantially on the line 2—2 of Figure 1.

Figure 3 is a view in front elevation of the back sheet of the calendar.

Referring now to the drawings in detail, it will be seen that the reference numeral 1 designates a back sheet of suitable size, shape and material upon which a comparatively short front sheet 2, also of suitable size, shape and material, is superimposed and pivotally connected adjacent its upper end, as at 3, for swinging adjustment. The pivot 3 may be in the form of a rivet passing through openings provided therefor in the sheets 1 and 2. The back sheet 1 extends beyond the lower end of the front sheet 2.

On the lower portion of the back sheet 1 is an arcuate group of figures 4 arranged in nineteen columns and representing the days of the months, the lowest of the figures being the numeral 1 and the highest being the numeral 31. The figures 4 are arranged

in a predetermined order. Also, on the lower portion of the sheet 1 which extends beyond the sheet 2 are the columns of months 5 in a predetermined arrangement. In certain of the columns 5 appear the words "February Leap Year" and "January Leap Year". As will be seen, the names of the months in the columns 5 are abbreviated.

Above the group of figures 4 on the sheet 1 there is provided a table of years 6 arranged in groups, each group comprising seven columns designated by the reference numeral 7. At the top of each column 7 is a heading 8 in the form of a letter, said letters running consecutively from A to G, inclusive, for each group of the year columns. Then, above the table 6, on the sheet 1 there may be defined a space 9 in which instructions for use in the calendar may appear.

In the lower portion of the sheet 2 is an arcuate opening or window 10 through which the figures 4 may be observed. The opening or window 10 is of the size to expose seven of the columns of figures 4. Immediately above the window or opening 10 the sheet 2 is provided with indicia in the form of letters 11 representing the days of the week consecutively. The spacing of the letters 11 correspond to the spacing of the columns of figures 4. Below the opening or window 10 and closely adjacent the lower end of the sheet 2 are the letters 12 which correspond with the headings 8 of the table 6. The spacing of the letters 12 also correspond substantially to the spacing of the columns of figures 4. Mounted for sliding adjustment on the sheet 2 in the lower side of the window or opening 10 is an indicator or marker 13 for the letters 12.

To use the calendar for ascertaining the day of the week on which any date occurred or occurs in any of the years appearing in the table 6, the desired year is located in said table 6 and the heading 8 at the top of the column in which the year appears is noted. Then, the indicator or marker 13 is shifted to the corresponding letter 12 on the sheet 2. The sheet 2 is then swung on its pivot 3 until the indicator or marker 13 is adjacent the column 5 in which the desired month ap-

pears and the dates of that month of that year will then be exposed through the opening or window 10 beneath the correct day indicating letters 11. When the year is a leap year the column 5 is used in which the indicia "February Leap Year" or "January Leap Year" appears. In the table 6 the leap years are indicated by a dash adjacent thereto in the preceding column.

10 The major portion of the sheet 2 above the window 10 may be ornamented as desired or utilized for the display of any desired advertising or printed matter.

15 It is believed that the many advantages of a calendar in accordance with the present invention will be readily understood, and although the preferred embodiment of the invention is as illustrated and described, it is to be understood that changes in the details 20 of construction and in the combination and arrangement of parts may be resorted to which will fall within the scope of the invention as claimed.

What is claimed is:—

25 1. A calendar comprising a sheet having columns of numerals thereon representing the days of the months, another sheet pivotally mounted for swinging adjustment on the first named sheet having a window there- 30 in of a size to expose seven of the columns, the second named sheet further having characters thereon representing the days of the week located adjacent the window for disposition in alignment with the exposed 35 columns, the first named sheet further having columns of months thereon, and a marker slidably mounted on the second named sheet for coaction with the month column for indicating when the second named sheet is in the correct position to align the day characters with the correct columns comprising 40 the days of any month of a year.

45 2. A calendar comprising a back sheet having columns of numerals thereon representing the days of the months, a front sheet pivotally mounted for swinging adjustment on the back sheet having a window therein of a size to expose seven of the columns and further having characters thereon adjacent the 50 window for disposition in alignment with the exposed columns, said characters representing the days of the week, the back sheet including a portion extending beyond the front sheet having columns of months thereon, and 55 a marker adjustably mounted on the front sheet for coaction with the month columns for indicating when said front sheet is in the correct position to align the day characters with the correct first named columns comprising 60 the days of any month of the year.

65 3. A calendar comprising a back sheet having a table of years thereon, said years arranged in columns, a heading character at one end of each column, the back sheet further 70 having columns of numerals thereon repre-

senting the days of the months, said back sheet still further having columns of the months of the year thereon, a front sheet pivotally mounted for swinging adjustment on the back sheet having a window therein of a size to expose seven of the day columns, and further having characters thereon adjacent the window for disposition in alignment with the exposed day columns, said characters representing the days of the week, one edge 75 of the front sheet being spaced from the corresponding edge of the back sheet in a manner to expose the month columns on said back sheet, characters on the front sheet adjacent said one edge thereof corresponding to the 80 heading characters in the year table on the back sheet, and a marker adjustably mounted on the front sheet for disposition selectively adjacent the last named characters on the front sheet and for coaction with the month 85 columns on the back sheet for indicating when the front sheet is in the correct position to align the day characters with the correct columns comprising the date numerals.

In testimony whereof I affix my signature, 90
EDMUND S. DELANCY.
